UNITED STATES PATENT OFFICE

155,340

DESIGN FOR A LAMP STANDARD OR
SIMILAR ARTICLE

William B. Frisbie, Oakland, Calif.

Application August 9, 1948, Serial No. 147,995

Term of patent 7 years

(Cl. D48—20)

To all whom it may concern:

Be it known that I, William B. Frisbie, a citizen of the United States, residing at Oakland, in the county of Alameda and State of California, have invented a new, original, and ornamental Design for a Lamp Standard or Similar Article, of which the following is a specification, reference being had to the accompanying drawing, forming part thereof.

The single drawing figure is a perspective view of a lamp standard or similar article, showing my new design.

The dash lines shown in the drawing are for the purpose of illustrating a lamp shade and indicate the shade as being supported by the ornamental lamp standard.

I claim:

The ornamental design for a lamp standard or

similar article, substantially as shown and described.

WILLIAM B. FRISBIE.
